RECEPTACLE HOLDER

Clifford R. Munson and Arthur R. Gross, St. Paul,
Minn.; said Gross assignor to said Munson

Application August 20, 1938, Serial No. 226,006

2 Claims. (Cl. 248—163)

This invention relates to holders for retaining garbage cans and other exposed receptacles in upright position and off the ground to thereby prolong the life of the receptacles and to guard 5 against spilling of the contents either by accident or by winds, or by dogs or other animals seeking food.

It is an object of this invention to provide an unusually simple, inexpensive and strong 10 holder of this class.

Further objects are to render a holder of this class peculiarly rigid and strong by a novel arrangement of legs and connecting members and to reduce shipping costs by making the several 15 component members readily separable, of light weight and of such form that they may be placed in compact bundles, each containing the parts for a dozen or more holders.

The invention also includes certain other novel 20 features of construction which will be more fully pointed out in the following specification and claims.

In the drawing,

Figure 1 is a perspective view of our improved 25 holder;

Fig. 2 is a plan view of the same;

Fig. 3 is a side elevation of the holder with a 30 garbage can or the like, indicated in dotted lines, in the holder;

Fig. 4 is a fragmentary, horizontal section 35 through one of the legs taken on the line 4—4 of Fig. 3;

Fig. 5 is a vertical section taken on the line 40 5—5 of Fig. 3;

Fig. 6 is an elevation of one of the ring and leg 45 connections as viewed from the inside of the ring, and

Fig. 7 is an enlarged perspective view showing 50 the upper end of one of the legs.

The holder has a horizontally disposed ring 8 55 preferably constructed from a band of heavy gauge metal having its ends welded together and having cylindrical inner and outer surfaces. Three legs, indicated generally by the numeral 9, 45 are rigidly secured to the ring 8 at their upper ends and are spaced equally around the periphery of the ring. These legs are of channel shape, in cross section, each having a pair of longitudinally extending flanges 10, preferably disposed at an angle of about sixty degrees to each other. The upper and inner extremities of these flanges 60 are cut away to fit the ring 8 and to form shoulders 11 to engage the bottom of the ring 8. Each leg, between and above these shoulders, has a 65 perforation 12 to receive a bolt 13 for detachably

connecting the leg to the ring. As the channel-shaped legs are constructed from heavy gauge sheet metal, the shoulders 11 and bolts 13 engaging the rigid ring 8 afford very strong and rigid, as well as detachable, connections between 5 the legs and ring.

Extending horizontally beneath the ring 8 is a triangular member 14 having corner portions 15 fitting within the channels of the legs and rigidly connected to the legs by bolts 16. The 10 member 14 is constructed from a band of heavy gauge metal adapted to support a garbage can or other receptacle within the holder, as indicated by the numeral 17 in Fig. 3, and is disposed edge-wise to the bottom of the receptacle. The ends 15 of the band forming the member 14 are joined together by welding and the several side reaches of this member are equal and extend from leg to leg successively around the perimeter of the member so that the legs are rigidly joined together against movement to and from each other. When the bolts 16 are tightened the corner portions 15 are wedged forcibly between the rigid flanges 10 of the channel shaped legs.

The lower end of the legs are preferably pointed 20 to facilitate driving them into the ground and the legs may be extended into the ground to a depth such as that indicated by the numeral 18 in Fig. 3 so that the member 14 spaces the bottom of the receptacle from the ground. This 30 prevents freezing of the receptacle bottom to the ground in cold weather and guards against rapid deterioration by rusting. To afford an adjustment for receptacles of various heights, the legs are formed with a plurality of horizontal series 35 of perforations, as indicated at 19, to receive the bolts 16 at various heights.

Holders of various diameters and having interchangeable legs of various lengths are provided to accommodate receptacles of the several 40 sizes in common use. We make the legs of differing length interchangeable with the rings and member 14 of different diameters so that the stock of sizes required to be kept on hand to supply the market is reduced. For shipping, the 45 legs of the holders are detached from the rings 8 and members 14 and the parts for a large number of holders are placed in each bundle. This greatly reduces the shipping costs. Mechanically unskilled purchasers of the holders easily assemble them, following simple directions, because of the small number and simplicity of the parts.

In use, the holders prevent the receptacles 50 from being tipped over on their sides with consequent spilling of the contents either by acci- 55

dent, wind or dogs or other animals seeking food. The receptacles are securely held in spaced relation to the ground irrespective of whether the ground beneath is level, irregular or sloping. The 5 holders are used largely for garbage cans, but it will be evident that they may be used to hold tubs or pots of flowers, trash burners and other receptacles.

The total weight of the holder need not exceed 10 about five or five and one-half pounds in the largest size for a garbage can because of the form of the legs and interlocking connections with the ring 8 and member 14. Obviously the member 14 may be made with four or more equal 15 sides having corner portions interlocking with the leg flanges and having legs equal in number to the corners of the member.

In the appended claims we have used the term 20 "multi-lateral" to include such members although the holder is more rigid and less expensive when constructed with three legs and the triangular member 14.

Having described our invention, what we claim as new and desire to protect by Letters Patent is:

1. A holder of the class described comprising, a top ring, a plurality of legs each formed near its upper end to engage a horizontal surface of said ring at points spaced along said ring, a bolt securing each of said legs to said ring at a point spaced vertically and horizontally between said first-mentioned points of engagement with the ring and means rigidly connecting said legs together below said ring, said means affording a support for the bottom of a can or the like within said ring and said legs projecting down from said connecting means. 5

2. A holder of the class described comprising, a horizontally disposed ring, a plurality of legs each having a pair of longitudinally extending 15 flanges formed with horizontally disposed shoulders engaging said ring at points spaced along the same, a bolt securing each of said legs to said ring at a point spaced vertically and between said shoulders and means rigidly connecting said 20 legs together below said ring.
